FIRE EXTINGUISHING AND ALARM
APPARATUS

Ernest A. Lowe and John R. Hamilton, Cleveland Heights, Ohio, assignors to Automatic Sprinkler Company of America, Cleveland, Ohio, a corporation of Delaware

Application December 15, 1931, Serial No. 581,088

36 Claims. (Cl. 169—17)

This invention relates to improvements in automatic sprinkler and alarm mechanism.

It is a primary object of the invention to provide a system of this character of universal application such that it can be applied to any usual type of structure to be protected and which will operate uniformly under any normal temperature or other atmospheric conditions.

It is a further object to provide a mechanism of this character which will require a minimum of attention on the part of any attendant, and wherein the elements of the mechanism are so arranged, supported and related as not to become injured or otherwise out of order when in use.

The above and other objects will appear more fully from the following description when considered in connection with the drawings in which:

Fig. 1 is an elevational view, parts being in section, and illustrating one complete adaptation of the present invention.

Fig. 2 is a fragmentary perspective view of a group of the elements placed in a fire zone.

Fig. 3 is an enlarged vertical sectional view of one of the heat absorbing pressure producing elements constructed in accordance with our invention.

Figs. 4 and 5 are transverse sectional views of two forms of tube supports shown in Fig. 2.

Fig. 6 is a vertical sectional view through the main fluid supply valve and control unit therefor.

Fig. 7 is a vertical sectional view, parts being in section, of a portion of the control mechanism and illustrating the general relation of the release elements employed.

Fig. 8 is a horizontal fragmentary sectional view of the load supporting levers of the release.

Fig. 9 is a fragmentary sectional view of the diaphragm and housing and the associated escapement levers.

Fig. 10 is a sectional view on the line 10—10 of Fig. 9.

Fig. 11 is a horizontal sectional view of the manual reset lever employed.

Fig. 12 is a diagrammatic view illustrating the heat absorbing units placed in the different fire zones and the associated flow controlling units leading to the main pressure responsive device of the mechanism.

Fig. 13 is a vertical section view illustrating the manual gate valve operating shaft and the alarm valve controlled thereby.

Fig. 14 is a vertical sectional view of the float

chamber and valve controlling mechanism for automatically maintaining a substantially constant pressure in the distributing pipes and supplemental tubing.

Fig. 15 is a view similar to Fig. 14 but taken at right angles thereto.

Fig. 16 is a vertical sectional view through the air filter shown in Fig. 1.

Fig. 17 is a perspective view of the separated valve controlling elements controlled by the float 10 and serving to operate the air injector and alarm.

Figs. 18, 19 and 20 are elevational views of the float actuated valve operating weights illustrating three adjusted positions of the parts.

Fig. 21 is a fragmentary detail view of the fire alarm gong and siren employed.

Referring to the details of the drawings wherein there is illustrated a preferred adaptation of our invention, the main fluid supply pipe 24 for supplying fire extinguishing fluid under pressure is provided with a manual gate valve 25 and with an automatically controlled main supply valve 26 and automatically removable pressure retaining or check valve 23. The fluid supply is conducted from the source to the risers 27 and branch pipes 28 leading to the different fire zones. A separate or auxiliary water supply is shown at 29 for supplying fluid to operate the alarms, etc. in case the source at 24 should fail.

The gate valve 25 is controlled by means of the hand wheel 30 and valve operating shaft 31 (Fig. 13) placed within the yoke 32. The shaft 31 as shown in detail in Fig. 13 is formed with a recess 33 for receiving the operating end of a valve lever 34 when the shaft is in closed valve condition.

The lever 34 controls a valve 35 for admitting water or other fluid from the pipe 36 leading from a suitable source of supply as for instance fluid supply pipe 24 below the gate valve 25 and with the alarm 40 shown as a siren operated by a fluid motor 40a. The pipe 36 communicating with the supply pipe 24 has also a communication with the pipe 37 leading from the auxiliary source 29 the latter source being thus available to operate alarm in case the source 24 should fail.

The mechanism associated with the gate valve 25 serves to operate the alarm, siren or signal 40 at all times the gate valve is in other than full open position. Said signal 40 is operated by a fluid motor supplied from pipe 39 and actuating motor driving wheel 40a all mounted in a suitable enclosure as shown. A suitable check valve as shown prevents the wa-

ter from source 24 from backing up into pipe 29.

There is also provided an electrically actuated alarm 43 adapted to be placed in closed circuit condition with its source of power 44 when the lever 34 is moved to position to open the valve 35. This is accomplished by providing the normally open contacts 45 in position to be engaged and closed by the lever 34 when the latter moves to position to open the valve 35. An operation 10 of the gate valve control wheel 30 thereby actuates the water actuating siren 40 and also the electric alarm 43. Hence, if the water operated alarm 40 should fail to sound for any reason when the gate valve is closed as for instance 15 through failure of water supply to said alarm, nevertheless a signal of the closure of said valve will be given on the electric alarm 43.

The particular construction of device and the manner of operating the same from the gate valve 20 stem are not herein claimed as they form the subject of our application for patent filed August 31, 1932, Serial No. 631,132.

An electric alarm 41 may be provided and controlled by a switch 42 operated by a pressure 25 responsive diaphragm, the latter communicating with the pipe 39 to cause the alarm 41 to be actuated at any time water pressure is supplied to the piping 39. By this means an alarm will be given in case the fluid operated devices for actuating the alarm 40 should fail to function under the pressure afforded by pipe 39.

There is also provided an electric alarm 41', controlled by a switch 42' operated by a flexible diaphragm which communicates with the pipe 35 56 for actuating this alarm coincidently with the fire alarm 55.

The main fluid supply valve 26 is formed with a valve chamber 46 for receiving the valve clapper 47 which serves when closed to shut off 40 the fluid supply between the source 24 and the risers and distributing pipes 27 and 28. The valve closure 41 is of a known type and includes the inwardly bent facing 48 cooperating with the valve seat 49 for effectively sealing the valve when 45 closed. The valve is held in closed position by means of a latch 50 pivoted to the valve casing at 51 and provided with an extension 52 extending through the opening 53 leading from the valve chamber 46 to the exterior air into position 50 for operation by hammer blow impact of a weight 64 as will be presently described. The latch 50 is provided with an outwardly opening sealing washer 54 cooperating with the valve seat at the opening 53 to close this opening when the latch 55 50 is moved to unlatched position.

It is preferred to associate a second fire gong or signal 55 with the apparatus constructed to be operated by the main water pressure supply. The gong 55 has a fluid actuating motor as indicated 60 similar to the fluid operated motor and alarm 40. Each alarm 40—55 is operated separately by its own driving fluid motor or driving wheel and both are mounted in one enclosing casing as shown, one of said gongs or alarms serving for 65 operation in connection with the gate valve while the other is used as a fire alarm signal or gong which will sound whenever the main valve opens in response to fire conditions in the fire area to be protected. The fluid motor of this fire gong is connected by the pipes 56 with the chamber 46 of the control valve so as to provide water pressure in the piping 56 for creating an alarm at 70 all times the main supply valve is in open condition. Pressure may be supplied by opening the 75

manual valve 57 for testing the apparatus when desired. The second signal 55 and its fluid actuated motor are mounted as shown in the same enclosure with signal 40 and its motor to form a single unit having the two protective signals each 5 fluid operated by fluid pressure derived from the desired source.

There is also provided an electric alarm 41' controlled by a switch 42' operated by a flexible diaphragm which communicates with pipe 56 for 10 actuating said alarm coincidently with the fire alarm 55 when the main supply valve opens. By this means we insure the giving of a fire alarm in connection with the opening of the main valve 15 even though the water supplied to the gong 55 should for any reason fail to bring about the action of the gong operating motor.

As will be presently described we further insure the sounding of a fire signal whenever the mechanism controlling the fluid supply is brought into 20 operation automatically by the pressure responsive release devices, through the provision of a circuit controller operable by a releasable weight released in the operation of causing the main valve or other fluid supply to become operative. 25

The release mechanism indicated generally at 30 58 is provided for the purpose of moving the latch 50 to unlatched position and is constructed to be actuated on either an increase or decrease of pressure in the supplemental tubing. The release box 59 carrying the main operating elements of the release is placed within a sealed chamber 60 having an outer casing 61 and closure plate 62. The sealed chamber or enclosure 60 for the main operating elements of the release 35 and for the feed ends of the supplemental tubing 184 (see Figs. 1, 6 and 12) has an unsealed chamber or housing 63 for receiving and housing operating weight 64 and associated parts. 40

The pressure responsive device 65 (Fig. 9) includes a diaphragm 66 mounted within a chamber 68 in the diaphragm casing 69. The diaphragm chamber 68 formed between the upper and lower cases 70 and 71 has two concave inner walls to permit the diaphragm to move toward 45 either side from the central neutral position in which it normally remains. It is preferred to employ two supporting plates 72 and 73 to reinforce the diaphragm at its center near the opening leading to the passage 74 in the upper case for 50 conveying pressure to the diaphragm and near the opening in the lower case in which the diaphragm plunger 75 is loosely mounted.

The vent 76 mounted in the upper diaphragm case 70 and communicating with the passage 74 55 is employed to gradually equalize the pressure in the supplemental tubing and on the upper face of the diaphragm 66 and supplied from chamber 60 with the pressure contained in the said chamber 60 (Fig. 6) and determines the rate at which 60 the pressure in the tubing must rise or fall in order to become effective in moving the diaphragm to effect a release. The vent comprises a relatively small tube 78 (Fig. 9) filled with fibrous packing and opening into the passage 74 at one end and into the interior of the chamber 60 at the other end. The outer end of the tube is covered over by a body of packing material 79 held in place by the apertured cap 80. The 65 fibrous packing filters the air passing to or from the supplemental tubing from the sealed casing 60 which is supplied with air under pressure from an air injector 184 as will be presently described. The air injector also has an air filter 220 inter- 70 75 75

posed in the air connection to the casing 60 and of a construction which will be described further on.

The plunger 75 is attached to the diaphragm 66 and to the escapement lever 81 as shown so as to transmit movement of the diaphragm in either direction into corresponding movement of the escapement lever. The lever 81 is normally retained in its central neutral position as shown by means of the tension spring 82. The lever 81 is formed with an angular projection 83 having a flat surface engageable edgewise against a corresponding projecting finger 84 formed on the escapement lever 85 held in place against the projection 83 by a spring 85. With this construction movement of the lever 81 in either direction releases the escapement levers 83 and 85 with the consequent operation of a main release lever 86 through action of the release elements 20 in the box 59 as will be presently described.

The main release lever 86 (Figs. 6 and 8) is pivotally mounted at 87 and is sealed with respect to the interior of the chamber 60 by means of the flexible diaphragm 88. The lever 86 is formed with a weight supporting projection 90 located in the outside chamber or housing 63 and with an operating pin 91 positioned in a slot 92 formed on the release operating lever 94 within the sealed chamber 60. The lever 94 is carried by a rock shaft 95 for movement therewith, the shaft 95 being also provided with a weighted lever 96 for returning the shaft 95 to its normal position as shown in Fig. 6.

The resetting lever 97 secured to the shaft 117 which carries lever 116 (see Fig. 7) and releases 94 (see Figs. 8 and 11) is formed with a slot 98 for receiving an operating finger 99 of the outside manual release lever 100. The lever 100 carried by a transverse pivot pin 101 and sealed 40 with respect to the interior of the casing 61 by means of a rubber or other diaphragm 102 is movable about the axis of the pin 101 for moving the resetting lever 97 to resetting position through an upward movement of the handle 103.

45 The weight 64 (Fig. 6) is movably supported and reciprocates vertically on a guide shaft 104 outside the release box 59 mounted in the unsealed protecting housing or chamber 63 which is suitably formed to allow access to the weight 50 for moving the same by hand or otherwise independently of the means for automatically releasing the weight. The guide 104 is pivotally connected at its lower end to the latch lever extension 52 and is supported for vertical movement 55 at its upper end by a guide 105 mounted independently of the weight guide. The weight when released creates a hammer blow on the latch lever extension 52 for unlatching the latch 50, thus bringing about the opening of the main 60 valve.

The weight 64 releasable and adapted when released to fall and strike the latch extension 52 is sustained in lifted position shown by means of a tiltable weighted latch lever 106 which is pivotally connected at 107 to the weight 64 and is biased by depending weight 106' on said latch lever so that when the weight is restored to latched position it will assume position for weight supporting engagement with the main release lever. The 70 latch lever 106 is formed with a supporting finger 108 engageable with the supporting projection 90 of said main release lever 86 to normally sustain the weight. When the main release lever 86 is freed by the action of the pressure controlled 75 release device in box 59, thus freeing the sup-

porting finger of the latch 106, the weight with the attached latch will fall. The latch lever 106 is also formed with an upwardly projecting finger or lug 109 normally engaging a detaining device consisting preferably of a slide bolt 110 5 for normally preventing tilting movement of the latch lever under the influence of the weight in a direction to free it from the supporting projection 90 of the main release lever 86. The detaining device or slide 110 is removable from detaining position by any desired means as for instance by means of the lever 111 and pull 112, said lever being connected with the slide 110 as shown or in any other suitable manner. A coil or other spring acts on the bolt to normally hold it down 15 in detaining position. The bolt might be operated also by a cable 113 extending from any convenient position where it may be operated by a pull to lift the bolt. When the slide or detaining device is removed from such detaining position, 20 the latch is free to be tilted by the influence of the weight 64 to which it is pivoted thus permitting the weight supporting finger 108 to slip by the projection 90 without movement of the release lever 86 which may at such time be in locked 25 position. The weight 64 is accessible through the wall of the housing so that it may be lifted and restored to position for being latched up until released by the action of the release lever 86. The mounting of the weight 64 and its attachments 30 in a suitable housing or casing outside the sealed enclosure or box 59 and its operating elements facilitates the operation of resetting and supervision of action of the weight and attachments and also contributes to ease of installation 35 of the apparatus.

An alarm or signal is provided whereby a signal will be given whenever the weight is dropped either through operation of the automatic release 86 or by the manually operated means 111 or 40 113 acting on the slide or detaining device 110. A convenient means for operating such signal comprises an electric switch and electric alarm bell controlled thereby. A form of switch adapted to function and sound the alarm or signal when 45 the weight falls or is released comprises switch contact 57' spring pressed towards closed position and normally held in open position by means of a switch finger engageable by the weight 64 when in sustained position. The switch when 50 closed on movement of the weight due to release thereof either by the automatic release lever 86 or by operation of the slide or detaining device 110 is employed to close the electric circuit through an alarm bell 57 and suitable source of 55 current supply. By means of the weight controlled circuit controller and alarm 57 we insure the giving of a signal or alarm although either or both the alarms 55 and 41' controlled or operated by fluid taken from the main valve chamber 26 should for any reason fail to operate, or if there should be failure of the main supply 24 or of the main valve 26 to operate thus opening the supply of fluid for operating said alarms 55 and 41'.

The release elements in box 59 (Fig. 6) operatively connected between the escapement lever 85 and the main release lever 86 (Fig. 8) for controlling the latter through movements of the former include the release operating lever 94, referred to above, and which is rigidly attached to the shaft 95. The free end 114 of the lever 94 engages beneath a shoulder 115 formed on the locking lever 116 (Fig. 7) the latter being pivotally mounted on the resetting shaft 117 which is 75

rotatably mounted in the release casing 59. The free end 118 of the lever 116 normally engages against the rearward cylindrical surface 120 constituting a keeper formed on the milled end of the hub or supporting shaft 121 of the operating lever 122. The projecting end 120 of the shaft 121 adjacent the surface 120 is formed with a milled end 123 to permit the lever end 118 to pass the same when the stud 121 is rotated to the proper position. The lever 116 is provided with a resetting pin 124 secured to the same and projecting through a slot 125 formed in the supporting plate 126, the slot accommodating the maximum movements of the lever 116 when moved 15 between normal and released positions.

The lever 122, formed integrally with or securely attached to the shaft 121, is formed with a weighted end 128 which tends to rotate the lever in a counter-clockwise direction as viewed in Fig. 20 7 and with an angular arm 129 provided with a pin 130 cooperating with the resetting devices of the release referred to below. The locking end 131 of the lever carries a pivotally mounted locking pawl 132 which in cooperation with a suitable 25 ratchet sustains the lever 122 in the position shown in Fig. 7. The pawl 132 is movable in a clockwise direction (as viewed in Fig. 7) to a limited extent only wherein it engages a stop pin 137, being normally held in engagement with the 30 pin by means of a spring 134. The pawl 132 is movable in a counter-clockwise direction to permit the locking end 135 formed on the pawl to move past the retaining portion of the ratchet device.

The ratchet device includes a rotatable spindle 35 136 formed with a ratchet tooth 138 engageable by the locking end 135 of the pawl when the parts are in their operative positions. The escapement lever 140 which controls the ratchet device is attached to the spindle 136 to cause the lever 143 40 and spindle 136 to rotate together. The outer movable end of the escapement lever is formed with an angular extension 141 (Fig. 9) positioned to be engaged by the cam-shaped finger 142 formed on the escapement fulcrum lever 85.

45 The supplemental tubing for conveying the pneumatic impulses from the various fire zones to the pressure responsive diaphragm 66 comprises the tubing 144 (Fig. 12) extending from the heat absorbing units 146 in the fire zone to the flow controlling units 148 and the tubing 149 connecting the various units 148 with the pressure responsive device 65. The units 148 are mounted within the chamber 60 adjacent to the hinged door 150 (Fig. 6). The units may be mounted 50 directly on the casing 61 or on the door 150 (see Fig. 6), the purpose being to surround the units 148 with the pressure in the chamber 60.

55 Each of the units 148 is formed with two sealing chambers 151 and 152 (Fig. 12). Chamber 60 151 communicates at its upper portion with the tubing 149 leading to pressure responsive device 65 and at its lower end is sealed by means of a tube 153, the lower end of which is immersed in a sealing liquid (mercury) 154. The tube 153 65 opens at its upper end into the chamber 152 which communicates directly with the tubing 144 leading to the fire zone and through the restricted vent 76' with the interior of the chamber 60. The chamber 152 also communicates through a 70 sealing tube 155 with the interior of the chamber 60, the tube 155 having its lower end immersed in the liquid (mercury) 156 and opening at its upper end in the chamber 60.

75 The tube 155 extends vertically above the liquid 156 to an extent sufficiently to effectively prevent

the passage of pressure from the chamber 152 through the tube 155 into the chamber 60 for any usual pressure to which the apparatus will be subjected in use, the enlargement 157 thereon being sufficient to receive and hold the liquid 156 5 in case the liquid should be accidentally forced through the tube 155. The lower end of the tube 155 is immersed only to a slight extent in the liquid 156 so that pressure passes readily from the chamber 60 inwardly through the tube 155 10 to the chamber 152 and thence to the tubing 144 or to the chamber 151 and tubing 149.

The tubing 144 is preferably of a height for maintaining sufficient pressure in the chamber 151 to flex the diaphragm 66 and operate the 15 release, the necessary margin of safety being provided. Any excess pressure in the tubing 144 and chamber 151 forces the mercury 154 upwardly into the chamber 152 where it remains until the increased air pressure at 152 ceases after which 20 the mercury again passes downwardly through the tube 153 and effectively seals the lower end of this tube as shown in Fig. 12.

Each of the sets of heat absorbing elements 146 is placed in a separate fire zone and due 25 to the sealing effect of the tubes 153 and 155 the pneumatic impulse in any set of heat absorbing elements 146 and tubing 144 from any fire zone is conveyed directly to the diaphragm 66 30 at least to an extent sufficient to actuate the release since the tubes 153 are immersed only slightly in the liquid 154 yet the vertical height of other tubes 153 is sufficient to create a release operating pressure.

Briefly, the system operates as follows:—after 35 closing the entire system at atmospheric pressure—1 lb. pressure above atmosphere is impressed on the inleading air pipe to enclosing casing (this 1 lb. pressure passes by flap check valve in air pipe) and into casing 60. It is free to 40 pass seal 156 and 154 into tubes 144, heat devices 146 and tube 149 and space 68. Vents 76'—76 45 relatively assist in passing this pressure as above described; after a period of time the 1 lb. pressure is equal in tubing 144—144 and chamber 60, thus being balanced equally on both sides of diaphragm 66.

Vents 76 and 76' are adjusted to equalize difference in pressure between chamber 60 and thermal system 144—149—146 due to local temperature fluctuation in region of 146 before such difference in pressure reaches the critical operating point of 66 and 81.

Fire in region of 146 produces an abnormal 55 pressure in 144 exceeding the equalizing adjustments of 76 and 76' and being stopped from loss to chamber 60 by tube 155 and seal 156 is free to pass seal 154 into tube 149 and chamber 68—moving diaphragm 66—operating detent 81. This fire pressure is checked against loss to other 60 tubes by tube 153 and seal 154, and also by vent 76; critical operating point of detent 81 is reached before 156 and 155 permit such fire pressure to escape into chamber 60.

Should a break occur in 144 or 146, this would 65 allow the 1 lb. pressure in 144 or 146 to escape to atmosphere, creating an impulse in 149—144 moving in the reverse direction than that from fire impulse since the break lowers the pressure in 144—146, and seal 154 permits the higher 70 pressure in 149 and 68 and other connected tubes 144 to freely pass and discharge out of the broken tube 144, seal 156 and vents 76—76' being sufficient to check against the higher pressure in 60 escaping, except by slow equalization 75

to the break so that diaphragm 66 moves inwardly due to the temporarily retained higher pressure in chamber 60.

A break in the enclosing case around chamber 60 permits escape of pressure in 60, lowering such pressure and moving diaphragm 66 outwardly to operate detent 81 by reason of the higher pressure being retained in 144—146—149; tube 155 retains this higher pressure up to and 10 safely beyond operating point of diaphragm 66 and detent 81.

Through the use of the units 148 the normal pressures developed in the tubing leading from any fire zone are equalized with the pressure 15 in the chamber 60 through the restricted vent 78. When any abnormally high pressure develops in the tubing 144 or 149 it is permitted to escape through the tubes 153 and 155 in order to prevent damage to the tubing or its associated devices under abnormal conditions and 20 after the operation of the release.

The heat absorbing units 146 each comprise a casing 158 (Fig. 3) connected to tubing 144 and mounted adjacent the ceiling of the room on a bracket 159. The units are preferably mounted 25 within the skeleton framework 160, the two halves of which are latched together as at 161, the upper half being secured to an attachment plate 162 formed with a hooked end 163 secured 30 within a recess in the bracket 159.

Each unit 146 is provided with an automatic device for opening the interior of the casing to the outside air on the attainment of a fixed relatively high temperature. In the present embodiment this device comprises a sleeve 164 permanently mounted at the lower portion of the casing 158 and receiving a sleeve nut 165 having an opening at its lower end corresponding to the opening within the sleeve 164. A fusible metallic washer 166 is held in position by the lower 40 end of the nut 165 and normally closes and seals the lower end of the sleeve 164. A hollow tube 169 is formed at its upper end with an enlargement 171 engageable against the upper end of the sleeve 164 when the tube falls to prevent the tube from dropping completely out of the casing, the tube being normally sustained in the elevated position shown by means of the fusible washer 166. The lower portion of each tube 169 45 is preferably painted some bright color as red or white so as to be readily seen and distinguished from the unit proper when exposed.

The pressure conveying tubing 144 is preferably supported on the distributing pipes by 55 means of the novel supporting devices disclosed herein which include a series of clamping elements 172 (Figs. 2 and 4) comprising C-shaped bands 173 each having an opening 174 sufficiently large to receive the particular size of distributing pipe 28 on which it is supported. A space is provided at one end of each band for receiving a channelled wedge-shaped securing element 175 received over the tubing 144 and constructed to be wedged between the end of the member 173 and the pipe 28. The elements 175 provide guiding channels having sufficient space for loosely receiving and holding in position a section of the supplemental tubing. The adjustable strap 173a 60 may be used in place of the C-shaped band 173.

In some portions of the apparatus the tubing may be supported in suitably attached brackets 176 provided with an aperture or with a slot for receiving the tubing. In other portions of 70 the apparatus the tubing is supported by having

the wedge shaped T 175 received within the supporting hanger 173.

The supplemental tubing is protected adjacent the sprinkler outlets 178 by means of the inverted cupped guards 179, each formed with an attachment portion 180 and with an outer flanged edge 181 which extends semi-circumferentially around the axis of the sprinkler outlet to provide an inverted pocket 182 for receiving and protecting the tubing. 10

Pressure is automatically maintained in the distributing pipes and supplemental tubing by means of the air injector indicated generally at 184 (Fig. 14). In our preferred construction we employ an air pressure supply consisting of a 15 water operated injector or inspirator acting on the Venturi principle, wherein the water necessarily comes into contact with the air so that the air tends to become laden with moisture. The form of such injector or inspirator 184 herein shown comprises a float chamber 185 and a liquid chamber 186, the latter having a relatively greater height compared with the float chamber 185. The two chambers communicate at their lower ends as indicated at 188 and the liquid chamber 20 186 is provided with an overflow outlet 189 at its upper end. Air is supplied to the pipes and tubing by means of a water actuated air injector 208 and admission valve 204 therefor controlled by a float 190 positioned in the float chamber 185 25 and weighted as indicated at 191 in order to provide the necessary weight. The float is loosely mounted on a hollow control shaft 192, being limited in its movements with respect to the shaft by means of the stops 193 and 194. The 30 shaft 192 is guided in its movements by means of a lower guide rod 195 positioned within the shaft 192 and connected to a removable plug 196 attached to a lower wall of the float chamber.

The upper end of the shaft 192 is pivotally 40 connected to an arm 197 of the operating quadrant 198 mounted for pivotal movement on the transverse shaft 200. This quadrant carries two operating pins E_p and A_p one on each face thereof, the pin E_p coacting with the limit pins E₂ and 45 E₁ positioned on the shiftable ejector actuating weight E and pin A_p coacting with the pins A₂ and A₁ on the shiftable alarm actuating weight A. The weighted elements E and A are formed with 50 openings E_o and A_o for receiving one of the operating sectors 199. These sectors are each formed with an arcuate section 201 received within the openings E_o and A_o and terminating in engagement fingers 202, the fingers being engageable by the weighted members E and A when the latter are moved beyond their dead center in one direction or the other. The sectors 199 are 55 formed with the operating fingers 203 operatively connected with the fluid control valves 204 and 205. These valves are of a known type and each includes a shiftable element 206 (Fig. 20) movable to or from closed valve position by means of the sectors 199.

The valve 204 controls the admission of water from the pipe 207 connected with the two sources, 60 (main fluid supply 24 and an auxiliary supply 29) and with the water actuated air injector or ejector-inspirator 208. The latter draws air inwardly through the air pipe 209 and forces the air and liquid inwardly through the pipe 210 65 extending into the lower portion of float chamber 185. The ejector-inspirator 208 is of a known type operating on the Venturi principle to entrain a quantity of air with the liquid passing into the chamber 185. The air and liquid 70 separating

- rate by gravity in the chamber 185 thus gradually building up the air pressure in the upper portion of the chamber and lowering the liquid level at the float 190. The excess liquid overflows 5 at 189 leading to the drain outlet and the air passes by outlet pipe 215 in the upper portion of the chamber 185 through the drier and filter 220 and pipes 221 and 222 to the sealed chamber 60 and the supplemental or pressure conveying detector tubing 144 with its moisture picked up in the inspirator removed. The pipe 215 also connects to the distributing pipe by a pipe 216 to maintain definite pressure therein from the air chamber 185 of the injector.
- 15 The valve 205 controls the admission of water from a branch of pipe 207 which communicates through the valve with a pipe 212 (Fig. 1) leading to the pipe 39 which in turn leads to the water motor 40a of the siren 40.
- 20 The pins E_p and A_p and the coacting pins E_2 , E_1 , A_2 and A_1 are coordinated with respect to the axis of the shaft 200 (see Figs. 17 to 20) so that weight E is shifted to operative (valve open) position when the float 190 has risen to substantially the level b (Fig. 15). On a further rise of the float to approximately the level c the weight A is moved beyond dead center to its operative position for supplying power through the valve 205 for actuating the alarm 40.
- 25 The various conditions of operation of the quadrant 198 are indicated in Figs. 18, 19 and 20. In Fig. 18 the float is assumed to be at the level a in the float chamber (Fig. 15) and the maximum pressure is present in the chamber 185. As the pressure decreases the water passes from the liquid chamber 186 into the float chamber 185 thus raising the float and causing a corresponding clockwise movement of the operating quadrant 198. As the arm 197 is raised the pin E_p ,
- 30 first engages the pin E_1 on the weight E . Further upward movement of the float throws the weight E beyond dead center thus shifting the valve 204 and turning on the liquid for actuating the air inspirator. This condition of the weights is indicated in Fig. 19.
- 35 Normally the inspirator replenishes the pressure and the float drops down to its normal position, shifting the weight E again to its inoperative position. If, however, the inspirator does not renew the pressure due to a serious rupture in the tubing or pipes or if the main water supply
- 40 for the inspirator should fail from any cause when the inspirator is called into action by the effects of the predetermined air leak 245 acting
- 45 independently of piping leaks the float continues to rise carrying with it the arm 197 until the pin A_p engages the pin A_1 on the weighted element A , this element finally being thrown beyond its dead center position to the position shown in Fig. 20
- 50 and producing the actuation of the alarm valve controlled thereby. As the pressure is replenished the reverse operation takes place and the alarm valve is first shut off and then the inspirator valve is shut off as the float reaches the
- 55 level a in the lower portion of the float chamber. This condition is indicated in Fig. 18.
- 60 The air in float chamber 185 is connected to the system of distributing pipes and to the supplemental tubing to maintain a definite pressure condition in the pipes and tubing. The connection from the float chamber to the distributing pipes is by way of conducting pipes 215 and 216, the latter entering the distributing pipes just above the back pressure valve 23. Check valve
- 65 217 prevents air pressure or water from passing

from the distributing pipes back into pipe 216 and the control valve has operated.

The air connection from the float chamber 185 to the supplemental tubing includes the pipe 218 leading to the air filter 220 which is connected 5 by way of pipes 221 and 222 and one way valve 223 with the interior of chamber 60 at the release mechanism.

The filter comprises an outer casing 224 (Fig. 16) having a connection with the pipe 218 leading 10 as just stated from the air chamber of the air injector or pressure producing device 184, the upper portion of the casing being closed by a cap 225 and the lower portion by means of a connecting plug 226. An intermediate cylindrical 15 member or tube 228 within casing 224 is attached to the plug 226 and itself carries an additional closure cap 229, the intermediate member 228 being spaced from the wall of casing 224 and terminating short of the top of this wall to provide an upwardly extending cylindrical passage 230 which is in communication with the top of the downwardly extending passage 231 between the inner cylindrical wall of tubular member 228 and an inner cylindrical member or chamber 232. 25 The latter is held at its top within a recess in an upper closure plug 233 carried by the cap 225 and is received within a similar seat in a lower closure plug 234 carried by the closure 229 so as to be held in position between these plugs. The 30 inner chamber or member 232 communicates at its lower end through a series of openings 235 with a chamber 239 in the closure 229 at the lower end of the space of passage 231 surrounding the same and connects at its upper end with the pipe 35 221 leading to the chamber 60. The interior of the inner member or chamber 232 contains a porous body of moisture absorbing material such as calcium carbide, indicated at 236. This porous mass of material acts also as an air filter for 40 straining dust or other impurities from the air. It is held in position within the inner chamber 232 between the porous plugs 233.

As air is being introduced into the supplemental tubing through the air filter the heavy moisture 45 is taken from the air due to the contact of the air with the walls 224 and 228 of the air passage in the filter body. This moisture runs back into the liquid in the float chamber. Of the air that passes from said passage over the upper end of 50 the cylindrical member 228 and down through passage 231 some moisture condenses out of this air and settles into the chamber 239 at the lower end of the filter. This moisture may be periodically removed by removing the plug 234. As 55 the air passes upwardly through the filtering material 236 the remainder of the moisture is taken from the air so that only relatively dry air passes to the sealed air chamber 60 of the release.

In order to cause the periodic operation of the pressure renewing devices we have arranged a vent 240 of fixed capacity and communicating with the air pressure space at the top of float chamber of the air injector or inspirator 184 to permit the pressure therefrom to be gradually 65 dissipated thus bringing about the periodic operation of the air injector. The vent disclosed may be as indicated at 245, Fig. 1 of the same type as vent 76 for equalizing the pressure between the supplemental tubing and sealed chamber 60 70 although it will be understood that other types may be provided at 240 and that this vent or restricted outlet may be of variable capacity if desired.

In the operation of the above apparatus pres- 75

sure greater than atmospheric pressure is normally maintained in the distributing pipe and in the supplemental tubing. If a fire should occur adjacent any of the heat bulbs the increase in pressure is transmitted through the flow control units to the pressure responsive diaphragm in the release thus causing the actuation of the release mechanism and the opening of the main supply valve. If the temperature should rise very slowly so as not to operate the pressure responsive devices through the increase of pressure then on the attainment of a fixed relatively high temperature one of the fusible elements 166 will be destroyed and the corresponding unit 146 will be opened to the outside pressure. The normal increased pressure within the unit and the additional pressure which has been added thereto through the increase in temperature is thus suddenly released and the release is operated through decrease of pressure in the tubing 144, thereby opening the main fluid control valve 47. As will be seen each double check flow unit provided for each tube prevents dissipation in the connection of each of said tubes to a common connection and dissipation of effects due both to operating increase and to decrease of pressure arising in any or all of the others.

The operation of the main fluid control valve 47 just described is brought about as follows (see Fig. 12):

Assuming that the manual pressure established by inspirator to be 1 lb., this pressure will be established in the distributing pipe system and in the chamber 60 and through the action previously described in the supplemental tubing 144 and the heat absorbing units 146. Should the fusible element 166 be melted by heat or a break occur in the supplemental tubing 144, the pressure in the heat absorbing units 146 and the supplemental tubing 144 would escape to the atmosphere while the pressure in the chamber 60 would of course endeavor to escape, the only avenues being through the restricted vents 76-76' and 155, the pressure at 152 will be less than at 151. Thus the greater pressure in 151 will lift mercury in the tube 153 until sufficient mercury has risen in 152 to leave the lower end of 153 open, when of course the pressure in 151 will then become the same as in 152. This drop in pressure will be transmitted through 149 to the upper surface of diaphragm 66, allowing the diaphragm to travel upward in response to the greater pressure remaining in 60. This will operate lever 81, moving projection 83 out of contact with projecting finger 84 (Fig. 9) thereby causing the release to operate and function fluid control valve 47.

When the apparatus is at rest the pressure in the inspirator 184 gradually decreases up to the point where the inspirator is brought into operation for bringing the pressure back to normal, a renewed supply of air being added directly to the distributing pipes and through the filter 220 to the supplemental control tubing. If the pressure in the piping or tubing should fall sufficiently low then the siren 40 is actuated to indicate the abnormal pressure condition in the system.

As will be seen, the system described permits balanced pressure other than atmosphere to be carried in chamber 60—tubing 149—144 and heat devices 146, equalizes by vents 76-76' unbalancing pressure fluctuations resulting from normal temperature changes in the region of 146—preventing operation of diaphragm 66 and detent 81 from normal temperature changes, and passes

operating pressures due to fire in region of 146 through seal 154 and 149 to space 68—thus moving diaphragm 66 outwardly and operating detent 81—without substantial loss of such pressure to chamber 60 or other tubing 144.

The system herein disclosed is of universal application in that it can be installed in heated or unheated buildings without danger of freezing any liquid in the distributing pipes or supplemental tubing. The system can protect a large area since the pneumatic control impulses originating in the different fire zones are isolated and conveyed directly to the main pressure responsive device 65. The complete system is supervised for the detection of any breaks in the pipes or tubing, the system being operated through the supplemental tubing on a predetermined rate of rise of temperature or in any event on the attainment of a fixed relatively high temperature. The mounting of the control tubing as herein disclosed affords additional dependability to the apparatus by affording maximum protection and secure supports for the tubing, which tubing however is exposed for inspection throughout most of its length.

It will be understood that pressure less than atmospheric may be employed instead of the increased pressure referred to herein and that various other adaptations of the invention may be made without departing from the spirit of the present invention.

Having now described our invention, we claim:

1. In a fire controlling apparatus provided with a system of pipes containing air under pressure, a sealed float chamber provided with an air pressure space communicating with said pipes at the upper portion of said chamber and containing a fluid column whose level changes with change in the air pressure in said pipes, a float buoyed in fluid in said chamber, a plurality of pivotally mounted weighted operating elements adapted to be tilted, means controlled by said float for moving one of said elements beyond dead center to operating position on a certain rise of said float due to change of fluid level and for moving the other said element on a further similar rise of said float, means controlled by one of said operating elements for supplying air to said float chamber and pipes and means controlled by the other said operating element for operating an alarm.

2. In a fire extinguishing apparatus, a system of pipes containing air under pressure, a sealed float chamber provided with an air pressure space communicating with said pipes and containing a fluid column whose level changes with changes in the air pressure in said pipes, a float buoyed in fluid in said chamber, pivotally mounted valve operating elements adapted to be moved past dead center and associated valves, means operatively connecting said operating elements with said float to be moved thereby when the level of fluid changes, said means causing one of said operating elements to be moved over pivotal center in advance of the other as said float rises with rise of fluid, an injector which simultaneously admits water and injects air into said chamber, said injector being operated by said element to be operated first and an alarm operated by the other said operating element.

3. In a fire extinguishing apparatus, a system of pipes containing air under pressure, a float chamber, a float buoyed in liquid in said chamber and rising and falling with rise and fall of the fluid level due to change of said air pressure upon

- the fluid, a plurality of pivoted weighted and shiftable operating elements, a float operated actuator for said operating elements, said actuator and operating elements having coacting abutments for causing said elements to be successively shifted past dead center, an injector operated by one of said operating elements and an alarm operated by the other and means for connecting said actuator to said float.
10. 4. In a fire extinguishing system for a plurality of fire zones, pressure producing devices in each fire zone, a main pressure responsive device and means of communication extending from each of said pressure producing devices to said pressure responsive device and each provided with a flow control unit permitting substantially unrestricted air flow toward said pressure responsive device but preventing the return passage of low pressures from said pressure responsive device to any of said pressure producing devices, said flow control unit permitting the passage of relatively higher pressures past the same in either direction.
15. 5. In a fire extinguishing system for a plurality of fire zones, pressure producing devices in each fire zone, a main pressure responsive device and means of communication extending from each of said pressure producing devices to said pressure responsive device, each provided with a flow control unit permitting substantially unrestricted air flow toward said pressure responsive device but preventing the return passage of low pressures from said pressure responsive device to any of said pressure producing devices, said flow control unit permitting the passage of relatively higher pressures past the same in either direction, and a casing enclosing said pressure responsive device and communicating with the rearward operating face of said pressure responsive device.
20. 6. In a fire extinguishing system for a plurality of fire zones, pressure producing devices in each fire zone, a main pressure responsive device and means of communication extending from each of said pressure producing devices to said pressure responsive device, each provided with a flow control unit permitting substantially unrestricted air flow toward said pressure responsive device but preventing the return passage of low pressures from said pressure responsive device to any of said pressure producing devices, said flow control unit permitting the passage of relatively higher pressures past the same in either direction, a casing enclosing said pressure responsive device and communicating with the rearward operating face of said pressure responsive device and means for gradually equalizing the pressure between the interior of said casing and within said means of communication.
25. 7. In a fire extinguishing system for a plurality of fire zones, pressure producing devices in each fire zone, a main pressure responsive device and means of communication extending from each of said pressure producing devices to said pressure responsive device, each provided with a flow control unit permitting substantially unrestricted air flow toward said pressure responsive device but preventing the return passage of low pressures from said pressure responsive device to any of said pressure producing devices, said flow control unit permitting the passage of relatively higher pressures past the same in either direction, a casing enclosing said pressure responsive device and communicating with the rearward operating force of said pressure responsive device, means permitting the free passage of air from said casing to the interior of said means of communication and means for supplying air pressure to said casing.
30. 8. In a fire controlling apparatus, pressure responsive means responsive to either an increase or decrease of pressure for bringing said apparatus into operation, a sealed heat responsive unit in a fire zone adapted to cause increase of pressure when heated and communicating with said pressure responsive means, means for unsealing said unit to cause relief of pressure and means for indicating the unsealed condition on attainment of a fixed relatively high temperature adjacent said unit.
35. 9. In a fire controlling apparatus, pressure responsive means responsive to either an increase or decrease of pressure for bringing said apparatus into operation, a sealed heat responsive unit in a fire zone communicating with said pressure responsive means, means for unsealing said unit to cause change of pressure on said pressure responsive means, and means connected therewith for causing visual indication of the unsealing of the same on the attainment of a fixed relatively high temperature adjacent said unit, said last named means comprising a plunger normally positioned mainly within said unit and retained therein by heat responsive means which frees said plunger for movement to a position exposing the same without said unit on the attainment of said relatively high temperature.
40. 10. In a fire extinguishing system provided with a distributing pipe, pneumatically actuated control means for controlling the admission of fire extinguishing fluid to said pipe and including pneumatic impulse conducting tubing, means for supporting said tubing on said pipe, said supporting means comprising an outer element loosely embracing said pipe, and a channeled intermediate member received within said outer element and coacting with said pipe for enclosing a section of said tubing.
45. 11. In a fire extinguishing system provided with a distributing pipe, pneumatically actuated control means for controlling the admission of fire extinguishing fluid to said pipe and including pneumatic impulse conducting tubing, means for supporting said tubing on said pipe, said supporting means comprising an outer element loosely embracing said pipe, and a channeled intermediate member of general wedge shape received within said outer element and coacting with said pipe for enclosing a section of said tubing, said intermediate member being formed with means for holding the same in its adjusted position with respect to said pipe.
50. 12. In a fire extinguishing system provided with a distributing pipe, a sprinkler head, means for securing said sprinkler head to said pipe, pneumatically actuated control means for controlling the admission of fire extinguishing fluid to said pipe and including pneumatic impulse conducting tubing, and means for supporting said tubing on said pipe, said supporting means comprising a shield formed with a semi-circular body part extending partially around said sprinkler head and having an outer wall spaced from said head to provide a longitudinal passage extending around said sprinkler head.
55. 13. In a fire extinguishing system provided with a distributing pipe, a sprinkler head, means for securing said sprinkler head to said pipe, pneumatically actuated control means for controlling the admission of fire extinguishing fluid to said pipe and including pneumatic impulse

conducting tubing, means for supporting said tubing on said pipe, said supporting means comprising a shield formed with a semi-circular body part extending partially around said sprinkler head and having an outer wall spaced from said head to provide a longitudinal passage extending around said sprinkler head and means for securing said shield beneath said sprinkler head.

14. In a fire extinguishing system provided with a set of fluid conducting pipes, means for maintaining pressure other than atmospheric pressure in said pipes and comprising an air pressure responsive mechanism for producing an air flow, and arbitrarily set means for gradually 10 venting the air in an air pressure chamber of said pressure maintaining means connected to said pipes up to the point at which said air pressure responsive mechanism will act to maintain the air pressure.

15. In a fire extinguishing system provided with a set of fluid conducting pipes, means for maintaining pressure other than atmospheric pressure in said pipes and comprising an air pressure responsive mechanism for producing an air flow 20 to maintain said pressure other than atmospheric, and a fixed leak for the said air under pressure in said conducting pipes operating on said pressure responsive means to cause periodical operation of the pressure maintaining means.

16. In a fire extinguishing system provided with a set of fluid conducting pipes, pneumatically actuated control means for controlling the admission of said fire extinguishing fluid to said pipes, a pneumatic impulse conducting tubing to said control means, air pressure producing means connected to said tubing, air pressure responsive mechanism controlling the action of the latter means and adapted to cause the same to operate on diminution of said air pressure and a fixed 30 air leak for periodically bringing the latter means into operation.

17. In a fire extinguishing system provided with a set of fluid conducting pipes, pneumatically actuated controlled means controlling the admission 40 of fire extinguishing fluid to said pipes and including pneumatic impulse conducting tubing having an air chamber connected thereto, an injector operating when the water in the chamber reaches a predetermined level simultaneously admitting water and injecting air into said chamber, said chamber having means for raising the water level therein upon decrease of the air pressure and for lowering the water level upon increase 50 of the air pressure, a float in said chamber controlling the action of said injector by the said rise and fall of the water level in said chamber, and a fixed air leak acting as a constant leak for the air supplied by the injector to the tubing for periodically bringing the injector into action 55 through the operation of the float.

18. In a fire extinguishing system, a pneumatic controlling device comprising a double acting diaphragm and means for operating said device on movement of the diaphragm in either direction, a system of tubing communicating with one side of said diaphragm, a closed casing enclosing said diaphragm and communicating with the opposite side of said diaphragm, means for introducing compressed air into said enclosing casing and a valve opening into said casing and into said tubing constructed and arranged for permitting passage of air from said tubing past said valve to the diaphragm but preventing the passage of 70 air from said diaphragm past the valve into said

tubing under normal conditions while permitting passage under abnormal conditions.

19. In a fire extinguishing system, the combination of distributing pipes, a main valve normally closed and adapted to admit fluid to the distributing pipes, a releasable actuating weight and means actuated thereby for freeing said main valve, a pivoted latch carried by said weight, a releasing member for releasing the same, means responsive to change of pressure generated by 10 heat in the fire zone for operating said releasing member and independent means for freeing the latch to permit the weight to fall while the pressure controlled releasing device is in operative position.

20. In a fire extinguishing apparatus provided with a distributing piping for the fire extinguishing fluid, a weight, a fluid supply means therefor and a control lever operated by said weight in falling and a guide for said weight pivotally connected at its lower end with said control lever and provided with a guide at its upper end.

21. In a fire extinguishing apparatus, the combination of a main valve, releasing means for the same, a weight adapted in falling to strike said releasing means, a tiltable latch mounted on said weight, a release lever adapted to engage with said latch and hold the weight in suspension and a detaining device normally engaged by said tiltable latch and provided with means for removing 30 it from engaging position to permit the weight to fall independently of the operation of said release lever.

22. In a release mechanism, a diaphragm, a housing therefor provided with a diaphragm 35 chamber having an outwardly bowed wall adjacent the opposite faces of said diaphragm limiting deflection of the diaphragm in both directions, said diaphragm chamber communicating freely with the outside air on one side of said 40 diaphragm and through an impedance with the other side of said diaphragm, means for conveying pneumatic pressure to the last named side of said diaphragm, a main release member and means for releasing said release member on movement of said diaphragm in either direction.

23. In a release mechanism, a diaphragm, a housing therefor provided with a diaphragm chamber having an outwardly bowed wall adjacent the opposite faces of said diaphragm limiting deflection of the diaphragm in both directions, said diaphragm chamber communicating with a pressure conveying conduit on one side of said diaphragm, a main release member and means for releasing said release member on movement of said diaphragm in either direction.

24. In a release mechanism, a diaphragm, a housing therefor provided with a diaphragm chamber having an outwardly bowed wall adjacent the opposite faces of said diaphragm limiting deflection of the diaphragm in both directions, said diaphragm chamber communicating with pressure conveying means on one side of said diaphragm, a main release member, means for releasing said main release member on movement of said diaphragm in either direction and means for normally retaining said diaphragm in a central neutral position.

25. In a release mechanism, a main release member, a pressure actuated member and release means for controlling said main release member on movement of said pressure actuated member, a sealed chamber enclosing said pressure actuated member, a resetting lever positioned without said chamber and sealed means 70 75

for transmitting power from said lever to said release means for resetting the same.

26. In a release mechanism, a main release weight, a tiltable latch lever carried by said release weight, pressure responsive means for releasing said weight and including a supporting element engageable beneath said tiltable latch lever, means engageable with said latch lever for normally retaining the same in operative position and secondary release means for moving said latch retaining means to inoperative position.

27. In a fire controlling apparatus, pressure responsive means responsive to a change of pressure for bringing said apparatus into operation, a sealed heat responsive unit in a fire zone adapted to cause increase of pressure when heated and communicating with said pressure responsive means, means for unsealing said unit to cause diminution of pressure and means for indicating the unsealed condition of said unit on the attainment of a relatively high temperature adjacent said unit.

28. In a fire extinguishing system, distributing pipes, a source of fire extinguishing fluid supply communicating with said pipes, means for controlling the passage of fluid from said source to said pipes, a fluid pressure actuated motor and alarm operated thereby, an auxiliary valve for closing off the supply of fluid from said pipes and controlling means and means for supplying fluid pressure to said motor from a source affording pressure when the auxiliary valve has been operated to closed position independent of that remaining in the pipes after the auxiliary valve is closed for giving a continuing alarm of full force by the action of the fluid motor so long as said auxiliary valve remains in closed position, and another alarm operable independent of the fluid pressure also put into action by operating the auxiliary valve to closed position.

29. In a fire controlling apparatus, distributing pipes for a fire extinguishing medium, means normally inactive adapted to supply said medium to said pipes, a latch normally holding the same out of action, a releasable weight adapted to engage the latch of said supply means by hammer action, a release lever for said weight, pressure operated detent mechanism for said release lever operated by pressure generated in the fire zone and contained in a sealed casing having a sealing opening through which said release lever extends, an exterior housing for said weight provided with a guide therefor and a releasing detent carried by said weight and engaged with the projecting end of the release lever projecting from said casing.

30. In a fire extinguishing system having distributing pipes for a fire extinguishing fluid, the combination of means for admitting said fluid to the piping, release devices pressure controlled and enclosed in a sealed chamber, a weight, an exterior housing therefor, a releasing member for said weight extending through a sealed opening in the chamber and a resetting device mounted in a sealed opening in said chamber and engaging said release devices for resetting the same.

31. In a fire extinguishing apparatus having a pressure controlled release the main operating

and releasing elements of which are enclosed within a sealed chamber maintained at a pressure of the pressure controlled release and an exterior resetting device extending through a sealed opening in said chamber and adapted to engage an operating element for the purpose of resetting the same.

32. In a fire extinguishing apparatus having a pressure controlled release the main operating elements of which are enclosed within a sealed chamber, an exterior resetting device extending through a sealed opening in said chamber and adapted to engage an operating element for the purpose of resetting the same, means for admitting fire extinguishing fluid to the piping, an operating weight therefor housed in an outside chamber and releasing catch for the weight controlled by an operating element of the release extending through a sealed opening in said chamber.

33. In a fire controlling apparatus distributing pipes for the fire extinguishing medium, a weight operated control for the supply therefor, a weight releasing lever mounted in a sealed casing and subject to the control of release detents in said casing pressure controlled from the fire area, and an exterior housing containing said weight, the said weight releasing lever extending through a sealing opening in the sealed casing for engagement with said weight.

34. In a fire extinguishing apparatus having a distributing piping, fluid supply means adapted to supply fire extinguishing fluid to said pipe, a catch normally holding said fluid supply means out of action, a release lever and pressure operated detent mechanism therefor both contained in a sealed casing and means controlling the catch of said fluid supply means mounted in a housing exterior to the sealed casing and in operative control engagement with the release lever by an extension of said release lever through a sealing opening in the sealed casing.

35. In a fire extinguishing system provided with a distributing pipe, a source of fire extinguishing fluid supply, gate valve controlling the passage of said fluid to the distributing pipes, a fluid pressure actuated alarm controlled by said gate valve and operated by pressure derived from the source of fluid supply admitted to said alarm on closing the gate valve and an auxiliary source of fluid supply supplying fluid through the controlling action of the gate valve independently of the supply derived from the extinguishing fluid.

36. In a fire extinguishing system, distributing pipes, a source of fire extinguishing fluid supply communicating with said pipes, a gate valve controlling the passage of said fluid to the pipes, a fluid pressure actuated alarm, means for admitting fluid from the source of supply to said alarm when the gate valve is closed and an auxiliary source of fluid supply connected to the gate valve and affording fluid pressure for actuating the alarm in case of failure of the alarm to operate by the pressure afforded by the fire extinguishing fluid.
